(57) **CLAIM**

What is claimed is; the ornamental design for, an automobile
and/or replica thereof, as shown and described.

DESCRIPTION

FIG. 1 is a first perspective view of an automobile and/or
replica thereof, showing our new design;

FIG. 2 is a second perspective view thereof;

FIG. 3 is a front elevation view thereof;

FIG. 4 is a rear elevation view thereof;

FIG. 5 is a top plan view thereof; and,

FIG. 6 is a right side elevation view thereof.

The left side elevation view is a mirror image of the right side
elevation view. The broken lines are for illustrative purposes
only and form no part of the claimed design.
